Patented Nov. 15, 1927.

UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

CORRUGATED CAR PART.

Application filed December 14, 1925. Serial No. 75,279.

The invention relates to parts for railway cars made of metallic plates reinforced and stiffened by integral embossments 1 or corrugations which terminate within the opposite ends 2 of the plate so as to provide marginal portions 3. Such marginal portions provide a place to attach means to stiffen the edges of the sheet or to attach it to the car.

10 In the drawings:

Fig. 1 shows an end of a railway car with my construction used thereon.

Fig. 2 is a section on line 2—2 of Fig. 1.

Fig. 3 is an enlarged fragmentary elevation of two metallic plates joined in accordance with my improvement.

Fig. 4 is a section on line 4—4 of Fig. 3.

In my construction I position an embossment near one side of the plate so that one of its walls forms a flange 4 at the edge of the plate, which flange is secured to a corresponding flange 5 on the adjacent plate. The rivet 6 (or other securing means) is located midway between the bounding planes of the embossed structure so that it is in the neutral axis of the section. The corrugated section is, therefore, now weakened by punching the holes for these rivets.

The edge flanges 5—6 of the adjacent plates merge into the original planes of the respective plates at 7 so that they lie in the same planes as the respective marginal portions. (A slight offset, of course, being required in one of the plates.) These flattened flange portions 7 are preferably secured together by one or more rivets 8.

The upper edge flange is preferably extended, as at 9, and bent to overlap the body portion of the other sheet and the sheets may be provided with flanges 10, if desired.

The construction may be used in a car wall, door or other part of the car and is especially adaptable where it is desirable that the joint between the sheets form a water-shed.

45 I claim:

1. In a railway car part comprising a metallic plate having an embossment adjacent one side forming an oblique flange at one edge, and another metallic plate having an oblique flange at one edge parallel to and secured to the upper side of the first mentioned flange.

2. In a railway car part comprising a metallic plate having an embossment adja-

cent one side forming an oblique flange at one edge, said embossment and flange merging into the original plane of the plate to form a flat margin, and another metallic plate having an oblique flange at one edge parallel to and secured to the first mentioned flange, said flange merging into the original plane of the plate to form a flat margin.

3. In a railway car part comprising a metallic plate having an embossment adjacent one side forming an oblique flange at one edge, said embossment and flange merging into the original plane of the plate to form a flat margin, and another metallic plate having an oblique flange at one edge parallel to and secured to the upper side of the first mentioned flange, said flange merging into the original plane of the plate to form a flat margin.

4. In a railway car part comprising a metallic plate having an embossment adjacent one side forming an oblique flange at one edge, said embossment and flange merging into the original plane of the plate to form a flat margin, and another metallic plate having an oblique flange at one edge parallel to and secured to the first mentioned flange, said flange merging into the original plane of the plate to form a flat margin which is secured to the corresponding flat margin, of the adjacent plate.

5. In a railway car part comprising a metallic plate having an embossment adjacent one side forming a flange at one edge, and another metallic plate having a flange at one side parallel to and secured to the upper side of the first mentioned flange.

6. In a railway car part comprising a metallic plate having an embossment adjacent one side forming a flange at one edge, said embossment and flange merging into the original plane of the plate to form a flat margin, and another metallic plate having a flange at one side parallel to and secured to said flange, said flange merging into the original plane of the plate to form a flat margin.

7. In a railway car part comprising a metallic plate having an embossment adjacent one side forming a flange at one edge, said embossment and flange merging into the original plane of the plate to form a flat margin, and another metallic plate having a flange at one side parallel to and secured to the first mentioned flange, said flange merg-

ing into the original plane of the plate to form a flat margin, which is secured to the corresponding flat margin of the adjacent plate.

- 5 8. In a railway car part comprising a metallic plate having an embossment adjacent one side forming a flange at one edge, and another metallic plate having a flange at one side parallel to and secured to the first mentioned flange, said flange extended and bent to overlap the embossment in the other sheet.
- 10 9. An end wall for a railway car com-

prising a lower metallic plate having an embossment at its upper side forming a flange 15 at its upper edge, and an upper metallic plate having a flange at its lower edge parallel to and secured to the upper side of the first mentioned flange.

- 10 20. An end wall for a railway car comprising a lower metallic plate having an embossment at its upper side, and an upper metallic plate having a partial embossment at its lower side overlapping and secured to the embossment in the lower plate.

GARTH G. GILPIN.
